UNITED STATES PATENT OFFICE.

NICKALOUS C. ZIRWES, OF SHEBOYGAN, WISCONSIN.

FOLDING CHAIR.

1,424,704.

Specification of Letters Patent. Patented Aug. 1, 1922.

Application filed February 18, 1921. Serial No. 445,987.

To all whom it may concern:

Be it known that I, NICKALOUS C. ZIRWES, a citizen of the United States, residing at Sheboygan, in the county of Sheboygan and 5 State of Wisconsin, have invented new and useful Improvements in Folding Chairs, of which the following is a specification.

This invention relates to a folding chair and has for its primary object the construction 10 of a device of this character that will be folded in a more compact arrangement and which may be readily carried.

An object of the invention is the construction 15 of a folding chair in which the parts are so arranged and constructed that they may be folded into a rectangular casing and may be very readily extended.

A feature of the invention is the novel manner of constructing and associating the 20 legs with the casing so that same may be quickly folded within the casing or extended therefrom and when in extended position have a mechanical connection with the casing in the manner to withstand excessive 25 strain.

With these and other objects in view the invention will be better understood from the following detailed description taken in connection with the accompanying drawings 30 wherein:

Fig. 1 is a side elevation of the invention.

Fig. 2 is a sectional view.

Fig. 3 is a vertical sectional view with the legs extended.

Fig. 4 is a sectional view with the parts folded.

Fig. 5 is a bottom plan view. Fig. 6 is a plan view of the seat member. Fig. 7 is a perspective view of one end portion of a leg.

Fig. 8 is an enlarged sectional view.

Again referring to the drawings illustrating one construction of my invention the numeral 1 designates a casing, shown in this particular instance as of rectangular configuration. The top 2 of the casing is provided with a threaded hole 4 for engagement with the screw 3 projecting from the folding seat member 5. It will be noted that the seat consists of three strips 6, 7 and 8 45 flexibly held together by the covering 9. Thus it will be seen that the strips may be folded in angular position to each other so as to be readily inserted into the casing in a manner hereinafter described. The open 50 bottom portion of the casing is provided

with slots 10 for the purpose now to be described. Slidably mounted within the casing is a block 11 to which are hinged the legs 12. The legs are provided with shoulders 13 of the proper inclination so that when 60 the parts are assembled these shoulders will bind against the outer surface of the casing and directly distribute the strain from the casing to the legs thereby preventing the hinged connections from being subject to excessive strain and besides to lock the legs to the casing. If found advantageous in practice a flexible element 14 may be connected to all the legs to reinforce same. To 65 complete the invention I provide a handle 15 secured to the casing so as to carry the chair when in folded condition.

From the foregoing description it will be seen that I provide a folding chair, the movable parts of which may be folded into 70 a very compact arrangement and besides when set up will be of substantial construction capable of sustaining great weight.

It is, of course, to be understood that the invention may be constructed in various 75 other manners and the parts associated in different relations and, therefore, I do not desire to be limited in any manner except as set forth in the claims hereunto appended.

Having thus described my invention what 80 I claim is:

1. A folding chair comprising a casing having slots formed in the bottom thereof, the upper wall thereof standing at an angle to the casing, and a slidably mounted block 90 within the casing and legs swingingly connected to the block and adapted to pass through said slot and bind against said inclined wall each leg being further provided with inclined shoulders binding against the 95 exterior surface of the case when in use.

2. A folding chair comprising a casing having slots formed in the bottom thereof, the upper wall thereof standing at an angle to the casing, a slidably mounted block with- 100 in the casing and legs swingingly connected to the block and adapted to pass through said slot and bind against said inclined wall each leg being further provided with inclined shoulders binding against the exterior 105 surface of the case when in use, a foldable seat member having screw threaded engagement with the top of the casing.

In testimony whereof I affix my signature,
NICKALOUS C. ZIRWES.
